UNITED STATES PATENT OFFICE.

IRA G. MITCHELL, OF MEeker, COLORADO.

STEP-LADDER.

1,134,214.

Specification of Letters Patent. Patented Apr. 6, 1915.

Application filed July 18, 1914. Serial No. 851,782.

To all whom it may concern:

Be it known that I, IRA G. MITCHELL, a citizen of the United States, residing at Meeker, in the county of Rio Blanco and

5 State of Colorado, have invented certain new and useful Improvements in Step-Ladders, of which the following is a specification, reference being had to the accompanying drawings.

10 My invention relates to certain new and useful improvements in means for securing safety in the use of ladders, and more particularly to step ladders.

It has for its object simplicity and economy in construction, ready attachment to ladders and effectiveness in use.

In order that others may know how to make my improved safety device and to apply the same to ladders and to also fully appreciate its advantages, I will proceed to describe the same, referring by numerals to the accompanying drawing, in which—

Figure 1 is a side elevation of an ordinary short step ladder equipped with a part 25 of my safety devices. Fig. 2 is an inside elevation of one side of a comparatively long step ladder and showing means auxiliary to that shown in Fig. 1, for securing safety. Fig. 3 is a vertical section on the 30 line X—X, of Fig. 2; and Fig. 4 is a detail section of the frame and foot shown in Fig. 1.

Similar reference numerals indicate like parts in the several figures of the drawing.

35 1 represents the sides of an ordinary step ladder, between and to which the steps 2 are secured in the usual way. The lower extremity of these sides are rounded as clearly shown in Fig. 4, and are located in a cast 40 metal shoe 3 and pivotally connected therewith by an ordinary screw bolt 4 and nut 5. The bottom or sole of this shoe is preferably formed with transverse dovetails in which are located leather or rubber friction 45 pads 6 to prevent any accidental slipping of the shoe, but in lieu of these pads, the sole may be corrugated or in any other suitable manner rendered anti-slipping. The bracing frame or prop 7 is also preferably 50 provided with shoes 3, of similar construction to that already referred to. In the ordinary step ladders of comparatively short height, I have found that by the use of friction shoes the ladder will not slip or spread 55 and that if so desired, the ordinary means for preventing the spreading may be dis-

pensed with, although if such means are employed, the friction shoes coöperate therewith and add greatly to the stability of the structure.

60 In cases of comparatively long or high ladders, additional safety means, such as shown in Figs. 2 and 3 are employed and in which 8 represents a metal frame secured by screws 9, to the inside 1 of the ladder. 65 This frame is recessed at the back to receive a sliding block 10 provided with a threaded stem 11 which projects through, and is slideable within a vertical slot 12, in the frame. The threaded stem is secured at its outer 70 end to a block or head 13, in which is pivotally located a prop 14 composed preferably of metal tubing of suitable stability, and between this head and the outer face of the frame 8, are arranged a washer or plate 75 15, and a wing nut 16, the latter threaded upon the stem, so that the prop may in an obvious manner be adjusted to any altitude with reference to the frame and then secured in fixed relation therewith by means 80 of the nut 16, when the prop has also been swung to the desired position. The free or lower end of this prop is preferably provided with a short sleeve 17 threaded to the prop and which is adapted to receive a friction pad 18, but in lieu of this construction, the end of the prop may be rendered anti-slipping in any other desired manner. For 85 convenience in moving or packing a step ladder, thus equipped, I provide the side 1, 90 with a pocket 19 adapted to receive the lower extremity of the prop to hold it against movement.

95 From the construction shown and described, it will be readily understood that the step ladder may be caused to assume any desired angle accordingly, as the prop 14 is adjusted.

100 From what has been described and shown, it will be seen that the major parts of my safety devices can be cheaply and quickly made by casting, and that the other and limited number of parts, are inexpensive and all can be readily assembled and disassembled and that they may be readily applied in operative relation with any ordinary step ladder, by simply rounding the bottom extremities of the ladder before securing the cast metal shoes thereon.

105 Having thus described this invention, what I claim is:—

The auxiliary brace or prop consisting of

a rearwardly recessed and vertically slotted frame; a block slidable within the recess of the frame and provided with a projecting threaded stem extending through the vertical slot and secured to an exterior head or block; a member pivotally connected with said block or head, and means surrounding the threaded stem and between the block or head and the face of the frame for securing

the vibrative member in any adjusted position, substantially as hereinbefore set forth.

In testimony whereof I hereunto affix my signature in the presence of two witnesses.

IRA G. MITCHELL.
